FUEL DISTRIBUTOR

Edwin Archer Turner, New York, N. Y., assignor
to The Standard Stoker Company, Incorporated,
a corporation of Delaware

Application May 9, 1930, Serial No. 450,891

5 Claims. (Cl. 110—101)

This invention relates to stokers, and more particularly to the distributing mechanism.

The principal object of the invention is the provision of new and improved means for distributing different sizes of fuel evenly over the grates or firebed.

Another object of the invention is the provision of new and improved means for separating the fine from the coarser fuel; for separating the lump fuel into different grades; and for simultaneously distributing the different grades of fuel to all parts of the firebox.

A further object of the invention is the provision of a new and improved fuel distributor member having a novel arrangement of steam jets thereon.

A still further object of the invention is the provision of new and improved distributing mechanism that is simple in construction, inexpensive to manufacture, and that is efficient and economical in operation.

Other and further objects and advantages of the invention will appear from the following description taken in connection with the accompanying drawings, in which

Fig. 1 is a central, longitudinal section of a locomotive and stoker with the invention in position thereon, parts being broken away;

Fig. 2 is a section on line 2—2 of Fig. 1;

Fig. 3 is a front elevation of the device when viewed from within the firebox;

Fig. 4 is a section on broken line 4—4 of Fig. 1; and

Fig. 5 is a section on line 5—5 of Fig. 2, showing the means for securing the distributor member in position.

In the use of stokers employing steam jets for projecting the fuel over the grates of the firebox, great difficulty has been experienced in distributing the fuel evenly over the firebed for the reason that it is common practice to use the run of mine coal in firing the boiler. In this type of fuel, the particles are of all sizes, and where large lumps occur coal crushers are commonly employed for reducing the size of the same and the crushing process results in the fuel being reduced to various sizes ranging in diameter from 4 inches down to pulverized material. The larger lumps being heavier require considerably more force to project them to the further end of the firebox than the pulverized material or the lumps of smaller size. A force, therefore, necessary to project any of the larger lumps of fuel to the further end of the firebox would be such as to project practically all the pulverized and smaller

lumps to the further end of the firebox, and as a result the fuel would be distributed unevenly over the firebed.

The present invention seeks to avoid this difficulty by the provision of means for segregating the pulverized material and separating the coarser material into a plurality of classes of different size lumps, together with means for utilizing steam at different pressures for projecting the different classes of material forward, whereby each class of material will be distributed substantially evenly over the entire firebed.

For convenience of description and simplicity in illustration, the invention is disclosed as being applied to a locomotive, but it is understood that the device is equally as applicable to stokers for other types of boilers.

Referring now to the drawings, numeral 10 designates generally a locomotive having a firebox 11 provided with a backwall 12 and grates 20 13. The backwall is provided with the conventional firedoor opening 14. Since the specific features of the locomotive constitute no part of the present invention, it is not thought necessary to further describe or illustrate the same.

Suitable stoker mechanism, designated generally by the reference numeral 15, is employed for conducting fuel from a source of supply, as the tender, to the firedoor opening. This mechanism comprises a conduit 16 terminating at its forward end in a riser conduit 17 having a removable cap 18 thereon; a distributor plate 19, and a distributor member 21 for projecting the fuel forwardly, as will presently appear.

The distributor plate 19 fits into a recess in the floor or bottom wall of the forward end of the riser conduit and is secured therein by bolts 22 engaging tapped holes in the flange 23 and seated in recesses 24 in the floor of said riser conduit, see Fig. 2. The forward end of this plate 40 extends into the firebox and is provided with curved channels 25 and curved abutments or abutment flanges 26 for directing fuel into the rear corners of the firebox.

The distributor member 21 comprises a body portion 27 which may be and preferably is rectangular at its rear end for engaging in a corresponding recess in the forward portion of the floor of the riser conduit 17, see Figs. 1 and 2. The distributor member is adapted to seat on the distributor plate 19 and is rigidly secured thereto by the bolts 28, the heads of which are seated in the recesses 29, see Figs. 2 and 5. The forward end of the body portion 27 is arcuate in order 55

that the fuel may be distributed to different parts of the firebox as will presently appear.

This distributor member is provided with means for separating the lump fuel into a plurality of classes, and for separating the finer or pulverized fuel from the coarser or lump fuel. In the form of construction selected to illustrate one embodiment of the invention the fuel is separated into three main classes, graded as to size. It is understood that this is by way of example only and that the principle employed may be extended for obtaining any desired number of classes graded as to the diameter of the material.

As shown, the body portion 27 is provided with a plurality of sets of forwardly extending projections or fingers 31 and 32. For the purpose of disclosure, only two sets of these projections are shown. The fingers 31 alternate with the fingers 32 and extend forwardly beyond the same. The ends of the fingers 31 terminate in a plane above and forwardly of the fingers or projections 32 whereby the steam passages extending through said fingers 31 will be above those extending through the fingers 32 for distributing the different sizes of fuel as will presently appear.

Both sets of fingers or projections may be and preferably are arranged radially whereby the fuel will be directed to all parts of the firebox.

The body of the distributor member 21 is provided with a plurality of steam chambers or headers 33, 34 and 35, three being shown. Preferably they are arranged one above the other. Their front wall is arcuate and suitable jet openings are provided through this front for each chamber. The jet openings 36 for the lowest chamber 35 extend through the wall below the plane of the fingers 32 while the jet openings 31 and 38 for the chambers 33 and 34 extend through the fingers 31 and 32 respectively.

Suitable means are provided for supplying steam at different pressures to the steam chambers. Since the least amount of steam pressure is required for projecting the finer particles forwardly, and the greatest amount for distributing the largest particles or lumps, the lowest chamber 35 is supplied with steam at the lowest pressure, the chamber 33 with steam at the highest pressure and the chamber 34 with steam at an intermediate pressure.

For convenience of description the chamber 33 will be referred to as the high pressure chamber, the chamber 34 as the intermediate pressure chamber, and the chamber 35 as the low pressure chamber.

Steam is supplied to the chambers 33, 34 and 35 by the pipes 41, 42 and 43 respectively. Valves 44, 45 and 46 may be provided in the pipes 41, 42 and 43 respectively for controlling the amount of steam supplied to the respective chambers.

The upper surfaces of the fingers slope downwardly and forwardly for facilitating the movement of the fuel thereover.

In the operation of the stoker, fuel is fed by the stoker mechanism onto the distributor member 21, pushed over the body 27 of the distributor member which may be curved to facilitate the passage of the fuel thereover, and forced forwardly onto the fingers. The pulverized and finer particles of fuel will fall down between the fingers and be projected forwardly and laterally by the steam jets 36. The intermediate size lumps will be forced forwardly over the outer ends of the fingers 32 and be distributed over the firebed by the steam jets issuing from the openings 37. The lumps of fuel that are too large to pass down

between the fingers 31 are pushed forwardly by the oncoming fuel and fall in front of the steam jets issuing from the jet openings 38 which distribute them evenly over the firebed.

The projection of the larger and intermediate lumps above the pulverized fuel will tend to form a blanket for preventing the finer particles of fuel from being caught by the draft and carried on to the stack.

A certain amount of fuel will, of course, be struck by the steam blasts in such a manner as to cause the same to strike the distributor plate and be directed by the channels 25 and abutment members 26 into the rear corners of the firebox.

I claim:

1. In a stoker, a riser conduit, a distributor plate detachably connected to the wall thereof over which the fuel is discharged and extending forwardly therefrom, a distributor member having steam passages opening through its front wall seated on the rear end of said plate, the aforesaid wall of said riser conduit being provided with a recess for receiving the rear portion of said member, and means for detachably connecting said member to said plate with the rear end of 25 said member in said recess.

2. In a stoker, a riser conduit, a distributor plate detachably connected to the wall thereof over which the fuel is discharged and extending forwardly therefrom, a distributor member having steam passages opening through its front wall seated on the rear end of said plate, the aforesaid wall of said riser conduit being provided with a recess for receiving the rear portion of said member, and means for detachably securing said member in said recess.

3. In a stoker, a fuel distributor member when in operative position including; an upstanding wall having an upper edge over which fuel drops in front of the wall, said front wall adjacent its lower edge having therein a transverse row of jet openings spaced between its ends, a transverse row of spaced fingers projecting forwardly from said front wall in a plane above said transverse row of jet openings, and a second transverse row 45 of spaced fingers projecting forwardly from said front wall a greater distance than and in a plane above the first row of fingers, said upper row of fingers being staggered with respect to the lower row and providing spaces therebetween, the upper 50 surfaces of the fingers of both rows extending rearwardly to said upper edge of the front wall to form channels therewith between the fingers, each of said fingers having a jet opening therein, and said distributor member having internal 55 chambers rearward of said front wall apertured for the introduction of pressure fluid in communication with the jet openings of the fingers and of the front wall for the supply of pressure fluid thereto.

4. In a stoker, a fuel distributor member when in operative position including; a top wall constituting a fuel receiving floor, a front wall extending downwardly from and transversely of said top wall at the discharge edge thereof, said front wall adjacent its lower edge having therein a transverse row of jet openings spaced between its ends, a transverse row of spaced fingers projecting forwardly from said front wall 70 in a plane above said transverse row of jet openings, and a second transverse row of spaced fingers projecting forwardly from said front wall a greater distance than and in a plane above the first row of fingers, said upper row of fingers 75

being staggered with respect to the lower row and providing spaces therebetween, the upper surfaces of the fingers of both rows extending rearwardly to the discharge edge of said top wall to form channels therewith between the fingers, each of said fingers having a jet opening therein, and said distributor member having internal chambers apertured for the introduction of pressure fluid in communication with the jet openings of the fingers and of the front wall for the supply of pressure fluid thereto.

5. In a stoker, a fuel distributor member when in operative position including: an upstanding wall having an upper edge over which fuel drops in front of the wall, said front wall adjacent its lower edge being apertured transversely between its ends to discharge pressure fluid forwardly in an approximately horizontal plane, a transverse

row of spaced fingers projecting forwardly from said front wall in a plane above the aforesaid plane, and a second transverse row of spaced fingers projecting forwardly from said front wall a greater distance than and in a plane above the first row of fingers, said upper row of fingers being staggered with respect to the lower row and providing spaces therebetween, the upper surfaces of the fingers of both rows extending rearwardly to said upper edge of the front wall to 10 form channels therewith between the fingers, each of said fingers having a jet opening therein, and said distributor member having internal pressure fluid supply chambers in communication with the jet openings of the fingers and with the 15 first named apertured portion of said front wall for the supply of pressure fluid thereto.

E. ARCHER TURNER.
